CONTAINER

Frank E. Chesney, Rocky River, Ohio, assignor to
The American Steel and Wire Company of New
Jersey, a corporation of New Jersey

Application December 17, 1946, Serial No. 716,755

8 Claims. (Cl. 220—5)

1

This invention relates to improvements in containers and in particular containers made in the form of a barrel or keg such as used for shipping nails, spikes, bolts and the like.

Among the objects of the invention is the provision of a container having a construction that combines lightness with strength which is simple, relatively inexpensive, and which can be quickly opened, and safely used thereafter.

It is a still further object of the invention to provide a container having a cylindrical sheet metal body having the ends substantially sealed by disk-like head members in which the head ends of the cylinder are constructed to tightly confine the heads therein and at the same time afford satisfactory resistance to forces tending to break the heads in or out of the container.

It is a further object of the invention to provide a container made in a plurality of sections so that the sections can be readily nested or stacked for stocking or for shipment to the point where the sections are to be assembled to complete the container for use.

These and further objects of the invention will be more readily apparent in the following description.

Desirable features for a container as described are economy, simplicity, lightness, and strength and these features are generally severally obtained, within practical limitations, in containers now in use. However containers, particularly nail kegs, are deficient in many respects, for example, wood stave kegs being made of strategic material in great demand for other purposes especially during periods of war are not always obtainable in the quantities required. Wood stave kegs, while satisfactory as to strength, are unnecessarily heavy and the combination of desired lightness with strength is missing. Furthermore, wood stave kegs having wood heads secured by nails driven through the staves into the heads present a hazard in use which is undesirable in that when the keg is opened, which is usually accomplished by bashing in the head by the sharp blow of a hammer and then removing the pieces forming the head, the nails are left sticking out through the staves inside the keg so when the hand and arm of a person is extended into the keg to remove nails, the members may be ripped and torn as they are removed. Also containers formed with steel bodies and wood heads used heretofore have also been deficient in simplicity and lightness combined with strength sufficient to resist crushing and breaking of the keg in service. Where nails have been

2

used to fasten the wood heads, the same hazard has been presented during its use. Where all steel containers have been used, it has been found that while the body portions have been generally satisfactory, it has been difficult to provide steel heads properly attached and readily removable without running into excessive cost which makes such a container commercially impractical and prohibitive for use in connection with such highly competitive products as nails, spikes, and the like.

The invention will be more readily understood by reference to the accompanying drawings, in which:

15 Figure 1 is a view in front elevation of a container constructed in accordance with the invention, a portion of the container being shown in longitudinal vertical section;

Figure 2 is a plan view of the container shown 20 in Figure 1;

Figure 3 is an enlarged vertical section on line III—III of Figure 2;

Figure 4 is a view in front elevation of a container constructed in accordance with the invention before the top head is applied and secured in place, a portion of the container being shown in longitudinal vertical section;

Figure 5 is a plan view of one of the sections of the container shown in Figure 4; and

30 Figure 6 is a vertical section on line VI—VI of Figure 5.

Referring in detail to the drawing which shows a preferred embodiment of the container of the invention, the numeral 10 represents generally 35 the main body portion of a cylindrical container or nail keg. This body portion comprises sections 11 and 12, these sections being identical, and each being substantially semi-cylindrical in form and having their longitudinal edges extending slightly beyond the diameter of the semi-cylinder to form laps 13 and 13a so that when the two sections are assembled together with their longitudinal edges overlapping, these lapped edges may be spot or tack welded together to form 40 a round hollow cylinder. In the preferred embodiment the body portion is composed of two semi-cylindrical sections, but it will be readily understood that the body portion can be constructed in as many sections as may be desired.

45 The sections 11 and 12 are preferably formed of sheet metal such as steel. The cylindrical body portion is also provided near each end with crozes 14 and 14a for the reception of disk-like head members 15 and 16. These head members 50 are preferably made of wood but if desired may

be formed of any other material such as metal, other fibrous material such as paper, pressed cloth, plastics, or earth materials such as are adapted to be formed into disks. Where fibrous materials or plastics are used, these may be reinforced by woven fabric of wire or textile material imbedded in the body of the head member.

Each of the container sections is provided near the top end with a pair of integral circular inwardly extending projections 17 and 18 and near the bottom end with a pair of similar projections 19 and 20. The two pairs of projections are preferably made substantially similar so that a description of one pair only will be necessary.

Projection 17 consists of a substantially perpendicular wall or abutment 21 having its innermost edge connected by a rounded nose portion 22 with an oblique wall 23. The oblique wall 23 is preferably extended toward the end of the container to connect with the cylindrical body portion at an adjacent angle A which may vary from 30° to 60° although containers having the said oblique wall extended at adjacent angles substantially less than 30° or more than 60° even approaching 90° may be used if desired and will give satisfactory results for certain uses. Projection 18 may be constructed similar to projection 17 with a substantially perpendicular wall or abutment 24 having its inner edge connected by a rounded nose portion 25 with an oblique wall 26 extending away from the end of the container. The two projections 17 and 18 may be positioned near the end of the container so that the abutments 21 and 24 will, together with the circular body portion 27 between the projections be adapted to form the croze 14 for the head member 15. Likewise, the two projections 19 and 20 may be similarly positioned to form the croze 14a for the head member 16. The two projections 17 and 18 are preferably arranged so that the abutments 21 and 24 will be spaced apart a distance slightly less than the thickness of the head member 15. The two projections 19 and 20 at the opposite end may be similarly spaced. By thus spacing the projections, the abutments of each pair will constrictingly retain the respective head members to make a tight package. If desired, however, the projections forming the crozes may be so positioned that the abutments will be spaced a distance substantially equal to the thickness of the head members which will adapt the crozes for retaining head members which may vary somewhat in thickness which often occurs in conventional cooperage.

By constructing the inwardly extending projections with substantially perpendicular abutments, as indicated at 21 and 24, supported by the oblique walls 23 and 26, as shown in Figure 3, reinforced shoulders are provided for the head member retained in the croze to thereby resist any forces either external or internal which would tend to break the head members in or out. These projections being extended inwardly and circularly will also function to strengthen the body of the container against radial forces tending to crush the cylindrical body.

Each pair of projections forming the crozes 14 and 14a is also preferably spaced from the end of the container a distance so as to provide a portion of the cylindrical body of the container next adjacent the end thereof so as to form a ledge or grip for the fingers of a person

or mechanical device when lifting or handling the container. When such a ledge or extension of the body portion is not provided next adjacent the end of the container then when the container is lifted or handled the lifting fingers often will slip over the edge of the container so that the container will be dropped usually on one corner of the container or keg. Such a concentration of force on the edge of the container is generally sufficient to break it open especially if the force is repeated. In order to prevent such breaking of the container, the pairs of projections forming the crozes may be spaced from the end of the container so that the distance from the surface of the head member nearest the end of the container to the end thereof is not substantially less than $\frac{3}{4}$ inch nor greater than $1\frac{1}{2}$ inches.

To provide a means for rolling the container during transportation, the container may be provided, intermediate its ends, with integral circular outwardly extending projections or beads 28 having tapered or flared side walls 29 which may extend outwardly sufficiently far to support the cylindrical body portion of the container away from contact with the floor or shipping dock. These outwardly extending projections also serve to further strengthen the body of the container.

So as to enable the shipment of tonnage of empty containers in freight cars, it is necessary that the sections of the containers stack or nest quite closely, otherwise the car space will be utilized before the tonnage allowance of the car is loaded.

In order to provide a close nesting of the containers in shipment the containers are made in sections as indicated in Figures 5 and 6. In constructing these sections, the outwardly extending projections 28 are extended outwardly farther away from the cylindrical body portion than the inwardly extending projections 17, 18, 19 and 20 are extended inwardly so that when the sections are nested together the outwardly extending projections 28 can be very readily aligned and this aligning and nesting of the sections is assisted by the tapered walls 29 of the projections 28.

In order to form and strengthen the chimes of the container, the ends of the sheets of the sections forming the container may be bent over as at 30 to form an outwardly and downwardly projecting annular bead. If desired, a metal wire not shown may be inserted in the cylindrical pocket formed by the bead 30 so as to reinforce the chime. In order to provide a smooth circular edge for the chime, a slot 31 may be provided in the chimes of each section having a length substantially equal to the length of the lap formed by the sections when they are assembled for welding the laps in forming the cylinder.

In constructing the container, two metal sheets of sufficient length and width to form the semi-cylindrical sections 11 and 12 are first sheared to size and the slots 31 punched out. These sheets are then passed through forming rolls to form the beads 30 to provide the chimes for the container. These beaded sheets are then rolled in forming rolls provided with suitable contours to form the semi-cylindrical section having the semi-circular inwardly and outwardly extending projections shown in Figures 5 and 6 which is the form in which the sections may be shipped to the place where the containers will be assembled for use usually a nail mill. At

this point two semi-cylindrical sections 33 and 34 will be assembled simultaneously with a head member 16 to form an open ended container 32 as shown in Figure 4 by clamping the sheet metal sections about the head member and spot or tack welding the longitudinal seams as indicated at 36. The welded container 32 having a bottom head member and having only a single integral circular inwardly-extending projection 37 adjacent the upper open-end of the container, as shown in Figure 4, may thereupon be filled with the articles for which the container is to be used. After the container has been filled, a head member such as shown at 15 in Figure 1 may be placed on the abutment 38 of the projection 37 after which the upper portion 39 of the cylindrical body of the container may be compressed in a suitable press having a die or dies reciprocating radially of the container to form the outer integral circular inwardly extending projection 17 to tightly secure the head member in the croze 14 thus formed to complete the container as shown in Figure 1. By suitably squeezing the container to form the projection 17 outside of the head member 15 of the container, the head member can be securely fastened in the croze without requiring any nails or other fasteners to hold the head members in place. Alternatively, the projection 17 may be formed by use of a roller bending device in which the container is mounted for rotation about its axis and one or more bending rolls are fed radially inward to engage the outer surface of the container above head 15 and to bend the container to form the projection. In order to later open the container to remove its contents, the head member can be bashed in by a sharp blow of a hammer and the pieces of the head member can be readily removed and a clear, free opening is provided for removing the contents.

If desired when forming the projection 17 in the closing of the container, the upper portion 39 of the cylindrical body of the container as well as the bead 30 for the upper chime may be reduced in diameter somewhat by a further compression of the clamp press so that the outside diameter of the upper chime will be smaller than the inside diameter of the chime at the bottom of the container, thus permitting the containers to be stacked one above the other with the bottom chime of the upper container in the pile nesting over the upper chime of the lower container. To permit such a reduction in the diameter of the upper chime, the slot 31 in the upper edges of the sections 11 and 12 of the container may be formed slightly longer than the lap in the sections so as to provide a smooth, continuous edge for the upper chime.

Although the keg above described has the cylindrical body thereof made up of two semi-cylindrical sections, kegs made in accordance with the present invention may, if desired, have such body formed from a single sheet. In such case the single sheet or keg blank, formed with the necessary beads and contours, will be shipped in a generally flat condition to the point at which the kegs are to be formed. The cylindrical body of the keg may then be formed from such blank by bending it into a cylinder and securing the ends of the sheet together as by spot welding.

While I have described preferred embodiments of the invention herein illustrated, it is to be understood that I am not limited thereto, since various modifications and substitutions of equiva-

lents may be made without departure from the invention as defined in the appended claims.

- I claim:
1. A container consisting of a cylindrical sheet metal body portion and disk-like head members enclosing the ends, the said body portion having a pair of integral circular inwardly extending projections adjacent each end, each said projection consisting of at least one substantially perpendicular abutment connected to a rounded nose portion, the said projections of each pair being spaced apart a distance substantially equal to the thickness of one of the said head members and being adapted to form with the contiguous body portion of the container a shouldered croze, the said head members being retained in the said crozes.
  2. A container consisting of a cylindrical sheet metal body portion and disk-like head members enclosing the ends, the said body portion having a pair of integral circular inwardly extending projections adjacent each end, each said projection consisting of a substantially perpendicular abutment connected by a rounded nose portion with an oblique wall, the said projections of each pair being spaced apart a distance slightly less than the thickness of one of the said head members and being adapted to form with the contiguous body portion between them a croze, the said head members being constrictingly retained in the crozes.
  3. A container consisting of a cylindrical sheet metal body portion and disk-like head members enclosing the ends, the said body portion consisting of a plurality of arcuate-shaped sections welded together and having a pair of integral circular inwardly extending projections adjacent each end, each said projection consisting of a substantially perpendicular abutment connected by a rounded nose portion with an oblique wall, the said projections of each pair being spaced apart a distance substantially equal to the thickness of one of the said head members and being adapted to form with the contiguous body portion between them a croze, each pair of the said projections being spaced from the ends of the container so that the distance from the outside surface of the head member retained in the croze to the end of the container is not substantially less than $\frac{3}{4}$ inch, the said body portion having a plurality of integral circular outwardly extending projections intermediate its ends, the said head members being retained in the said crozes.
  4. A container consisting of a cylindrical sheet metal body portion and disk-like head members enclosing the ends, the said body portion consisting of a plurality of arcuate-shaped sections welded together and having a pair of integral circular inwardly extending projections adjacent each end, each said projection consisting of a substantially perpendicular abutment connected by a rounded nose portion with an oblique wall disposed at an adjacent angle with the said body portion not substantially greater than 60° , the said projections of each pair being spaced apart a distance substantially equal to the thickness of one of the said head members and being adapted to form with the contiguous body portion of the container between them a croze, each pair of the said projections being spaced from the ends of the container so that the distance from the outside surface of the head member to the end of the container is not substantially less than $\frac{3}{4}$ inch, the said body portion having a plurality of integral circular outwardly extending projections in-

termediate its ends, the said head members being retained in the said crozes.

5. A section for a cylindrical container having a disk-like head member enclosing one end, said section consisting of an arcuate-shaped sheet metal body portion having a pair of integral arcuate inwardly extending projections adjacent one end, each said projection consisting of at least one substantially perpendicular abutment connected to a rounded nose portion, the said projections being spaced apart a distance substantially equal to the thickness of the said head member and being adapted to form with the contiguous body portion of the container a shoulered croze, and an integral arcuate inwardly extending projection similar to one of the projections of the said pair in the said body portion adjacent the opposite end.

6. A section for a cylindrical container having a disk-like head member enclosing one end, said section consisting of an arcuate-shaped sheet metal body portion having a pair of integral arcuate inwardly extending projections adjacent one end, each said projection consisting of a substantially perpendicular abutment connected by a rounded nose portion with an oblique wall, the said projections being spaced apart a distance substantially equal to the thickness of the said head member and adapted to form with the contiguous body portion a croze, and an integral arcuate inwardly extending projection similar to one of the projections of the said pair in the said body portion adjacent the opposite end.

7. A section for a cylindrical container having a disk-like head member enclosing one end, said section consisting of an arcuate-shaped sheet metal body portion having a pair of integral arcuate inwardly extending projections adjacent one end, each said projection consisting of a substantially perpendicular abutment connected by a rounded nose portion with an oblique wall, the said projections being spaced apart a distance substantially equal to the thickness of the said head member and adapted to form with the contiguous body portion a croze, and an integral arcuate inwardly extending projection similar to one of the projections of the said pair in the body

portion adjacent the opposite end, the said pair of projections being spaced from the end of the container so that the distance from the end of the said abutment of the inwardly extending projection nearest the end of the container to the end of the container is not substantially less than $\frac{3}{4}$ inch, the said body portion having a plurality of arcuate outwardly extending projections intermediate its ends.

8. A section for a cylindrical container having a disk-like head member enclosing one end, said section consisting of an arcuate-shaped sheet metal body portion having a pair of integral semi-circular inwardly extending projections adjacent one end, each said projection consisting of a substantially perpendicular abutment connected by a rounded nose portion with an oblique wall disposed at an adjacent angle with the said body portion not substantially greater than 60° , the said projections being spaced apart a distance substantially equal to the thickness of the said head member and adapted to form with the contiguous body portion a croze, and an integral arcuate inwardly extending projection similar to one of the projections of the said pair in the body portion adjacent the opposite end, the said pair of projections being spaced from the end of the container so that the distance from the said abutment of the inwardly extending projection nearest the end of the container to the end of the container is not substantially less than $\frac{3}{4}$ inch, the said body portion having a plurality of integral arcuate outwardly extending projections intermediate its ends.
